W. J. HENSEL.
SHOCK TYING DEVICE,
APPLICATION FILED JULY 23, 1920.

Patented Nov. 16, 1920.

William J. Hensel

INVENTOR.

Shepherd & Campbell ATTORNEY.

UNITED STATES PATENT OFFICE.

WILLIAM J. HENSEL, OF AUBURN, IOWA.

SHOCK-TYING DEVICE.

1,358,845.

Specification of Letters Patent. Patented Nov. 16, 1920.

Application filed July 23, 1920. Serial No. 398,458.

To all whom it may concern:

Be it known that I, WILLIAM J. HENSEL, a citizen of the United States, residing at Auburn, in the county of Sac and State of Iowa, have invented certain new and useful Improvements in Shock-Tying Devices, of which the following is a specification, reference being had therein to the accompanying drawings.

10 This invention relates to shock tying devices and it has for its object to provide a simple and inexpensive hand operated device adapted to be individually applied to shocks of grain and by means of which the 15 shocks may be tightly compressed and held in its compressed condition during the time that a cord is being tied around the same.

It is a further object of the invention to 20 provide a device of the character indicated constructed to give a firm bearing upon the shock and to be held against bodily turning with respect to the shock. The invention further contemplates the provision of improved means for increasing the rear end 25 bearing surface of the winding drum to resist lateral strain. A further object of the invention is the provision of an improved pawl and ratchet construction by means of which the device may be easily and quickly 30 controlled.

Further objects and advantages of the invention will be set forth in the detailed description which now follows.

In the accompanying drawing:

35 Figure 1 is a plan view of a shock compressing device constructed in accordance with the invention;

Fig. 2 is a partial front elevation thereof; and

40 Fig. 3 is a vertical longitudinal section through the winding drum.

Like numerals designate corresponding parts in all of the figures of the drawing.

Referring to the drawing it will be seen 45 that the device comprises a shaft 5 that is pointed at 6 to adapt it to be thrust into the body of a shock. The outer end of the shaft 5 provides a mounting for a rotative drum 7. A crank 8 carrying an operating handle 9 is secured to a flange 10 of the drum 7 at 11. A collar 12 carrying ratchet teeth 13 is pinned to the outer end of the shaft, the teeth of this ratchet being engageable by a pawl 15 that is pivoted at 16 to the crank 8. A link 17 connects the pawl 15 with an operating lever 18 that is pivoted at 19 to

the crank 8. The lever 18 carries an outwardly projecting finger engaging piece 20 by which the lever may be operated, and this finger engaging piece is projected inwardly beyond the lever 18 to engage in a detent recess 21 of the crank 8. A spring 22 tends to move the pawl 15 into engagement with the ratchet teeth but the frictional engagement of the inner end of the piece 20 in the detent recess 21 is sufficient to hold the pawl out of engagement against the action of the spring 22, when desired. An enlarged bearing flange 24 is pinned or otherwise secured at 25 to the shaft 5. A 70 curved guard strip 26 lies transversely with respect to the shaft 5, and the shaft 5 passes therethrough. Bearing elements 27 are secured to the flange 24 and the outer faces of these bearing elements lie flush with the outer face of the guard strip 26, with the result that a complete flat bearing for the entire inner face of the enlarged flange 28 at the inner end of the winding drum, is provided. Thus a part of the lateral strain 80 brought upon the winding drum is transmitted directly to the guard strip which engages over a considerable surface of the shock. This guard strip performs the additional function of holding the shaft 5 85 against turning in the shock. A strap 29 braces and strengthens the guard strip. The guard strip carries a hook 30 adapted to engage a loop 31 formed upon the end of the cord 32 by which the shock is to be tied 90 A rope or cable 33 has one of its ends permanently secured to a ring 34 that is carried by the drum 7. In operation the shaft 5 is thrust into the shock to be tied with the guards 26 firmly engaged with the face 95 of the shock to hold the device as a whole, against turning. The operator then forms a loop 31 in the cord by which the shock is to be tied, engages this loop with the hook 30 and carries the rope or cable 33 and 100 the cord around the shock together, being careful to keep the cord beneath the rope. After the shock has been encircled the end of the cord is left to hang freely, for the time being, while the free end of the rope is 105 engaged beneath that portion of the rope adjacent the ring 34. The operator then, through handle 9 and crank 8 rotates the drum to bodily wind the cable thereon, thus constricting the bight portion of the cable 110 and tightly compressing the shock against the guard strip 26 and ultimately constrict-

- ing it to a point where it is engaged, substantially, entirely therearound by the rope or cable. During the winding operation the pawl may be left in the position illustrated 5 in Fig. 2 to snap over the ratchet teeth, or it may be held out of engagement with said teeth during the winding operation, but in any event at the completion of the constricting operation the lever 18 is moved to such 10 position that the pawl is engaged with and held by the ratchet teeth, so that reverse movement of the drum is prevented. This leaves the hands of the operator free to complete the tying operation which is done 15 by drawing upon the free ends of the cord after removing the loop 31 from the hook 30 and sawing the cord back and forth until it is drawn up closely beneath the rope, then the free end of the cord is passed 20 through the loop 31 and tied after which the pawl may be disengaged from the ratchet teeth; the drum given a reverse movement and the device removed from the shock preparatory to repeating the operation 25 upon another shock.

From the foregoing description it will be seen that simple and efficient means are herein provided for accomplishing the objects of the invention; however, it is to be understood that the invention is not limited 30 to the precise construction set forth but that it includes within its purview whatever changes fairly come within either the terms or the spirit of the appended claims.

Having described my invention, what I claim is:

1. A device of the character described comprising a shock penetrating shaft, a guard strip through which said shaft passes, bearing elements the outer faces of which are flush with the outer faces of the guard strip to form a continuous flat bearing surface, a drum having an enlarged inner end flange bearing against said flat surface and 40 mounted for rotation upon the shaft, a pawl upon the shaft outwardly of said drum, an operating handle carried by the drum, a pawl carried by the handle and coacting with the ratchet and a cable permanently 45 attached to the drum and adapted to be wound thereon.

2. A device of the character described comprising a shock penetrating shaft, a guard strip extending transversely with respect to the shaft and through which the shaft passes, bearing elements carried by the shaft the outer faces of which lie flush with the outer face of the guard strip and a rotative drum upon the shaft outwardly of the guard strip, said drum having an enlarged inner end flange which bears against 55 said bearing element.

3. A device of the character described comprising a shock penetrating shaft, a drum mounted for rotation thereon, a pawl carried by an operating handle, the latter being secured to said drum, a fixed ratchet on the shaft with which the pawl coacts, an operating lever pivoted to the handle, a link connection between the operating lever and the pawl and a detent between the operating lever and the handle whereby the operating lever may be locked in position to hold the pawl out of engagement with its ratchet. 75

4. In a device of the character described the combination with a shock penetrating shaft, a transverse guard carried thereby, bearing elements located at the junction of the guard strip and the shaft, a drum disposed outwardly of said bearing element, said drum having an enlarged inner end flange coacting with said bearing element, a cord retaining hook upon the guard strip, a fixed pawl on the shaft outwardly of the 80 drum, a crank attached to the outer end of the drum, a pawl pivoted to the crank and coacting with the ratchet, an operating lever for the pawl pivoted to the crank, a link connection between the lever and the pawl, 90 a spring tending to move the pawl into engagement with the ratchet and a friction detent between the free ends of the operating lever and the crank for holding the lever in position to hold the pawl out of engagement with its ratchet, a cord retaining hook upon the guard strip and a cable permanently attached to the drum and adapted 95 to be wound thereon.

In testimony whereof I hereunto affix 100 my signature.

WILLIAM J. HENSEL.
